MILK COOLER

Richard Markley, Jr., Smyrna, Del., assignor to Wilson Cabinet Company, Smyrna, Del., a co-partnership, comprising John E. Wilson, Jr., and Bertha M. Wilson

Application October 22, 1942, Serial No. 462,976

6 Claims. (Cl. 62—101)

This invention relates to milk coolers of the general type disclosed in U. S. Patent No. 2,188,839.

The principal object of the invention is to provide a milk cooler which, while having all of the functional advantages and desirable characteristics of the cooler disclosed in the aforesaid patent, will still show a substantial improvement both in structural and functional respects over the milk coolers of the prior art.

A more specific object of the invention is to provide a milk cooler having an improved form of cooling element better adapted for milk-cooling purposes than the elements of the prior art.

Still another object of the invention is to materially simplify the internal structure of the cooler and to render it more readily cleanable and maintainable in sanitary condition.

The invention resides further in certain structural details and arrangements hereinafter described and illustrated in the attached drawings, in which:

Figure 1 is a longitudinal sectional view of a milk cooler made in accordance with a my invention;

Figure 2 is a sectional view on the line 2—2 of Figure 1;

Figure 3 is sectional view on the line 3—3 of Figure 1;

Figure 4 is a sectional view on the line 4—4 of Figure 1;

Figure 5 is an enlarged sectional view on the line 5—5 of Figure 1, and

Figure 6 is a fragmentary view in perspective illustrating a modification within the scope of the invention.

With reference to the drawings, the embodiment of the invention therein illustrated comprises an insulated cabinet 1 having at the top two hinged lids 2—2 affording access to the interior. As shown in Fig. 2, the lids 2 extend from the front wall 3 of the cabinet to a line short of the rear wall 4, the rear edges of the lids being hinged in each instance to a top wall section 5 which is held in place by means of screws 6. These top wall sections 5 are detachable from the body of the cabinet by withdrawal of the screws 6, for a purpose hereinafter described.

Intermediate the lids 2—2 and the associated top wall sections 5 and extending from the front wall 3 continuously to the back wall 4 of the cabinet is a top wall section 7, this section being suitably secured to the body of the cabinet. As illustrated in Figs. 1, 2 and 3, this top wall sec-

tion 7 forms a mounting for a refrigerating unit 8, this unit including an electric motor 9.

The interior of the cabinet 1 is divided into a plurality of compartments by longitudinal and transverse partitions 11 and 12 respectively. The partition 11 is positioned relatively close to the rear wall 4 of the cabinet so as to leave a narrow intervening chamber 13. The partition 12 extends from the front wall 3 to the partition 11 and divides the interior of the cabinet into two main compartments 14 and 15. This partition is somewhat higher than the partition 11, but its upper edge lies well below the tops of the cabinet walls, as illustrated in Fig. 2. In the present instance, the upper portion of the partition 12 extends over the partition 11 to the rear wall 4 and downwardly into the chamber 13 to a point below the upper edge of the partition 11. Thus, the partition 12 functions also to divide the upper portion of the chamber 13 at or near the longitudinal mid-section of the latter.

The partition 11 is of the form shown in Figs. 1 and 5. It consists of a metallic plate formed with interior channels 16 which extend longitudinally of the plate, and are connected at their ends in a manner to afford a tortuous passage extending from one longitudinal edge to the other, and in each pass embracing substantially the entire length of the plate. The partitioning plate 11 may be formed by welding together face to face two thin metallic plates 17 and 18, the plate 18 being shaped to afford the channels 16. In this manner, one face of the plate is left flat, and in the assembly the partition plate 11 is arranged in the cabinet so that the flat face is toward the front wall 3. This provides a flat smooth surface for abutment with the proximate edge of the partition 12 and simplifies the operation of making this joint a water-tight one.

As shown in Figs. 1, the lower run of the channel 16 extends upwardly through the plate at one end of the latter and terminates at 19 at the upper edge of the plate. The upper run of the channel 16 also terminates at one end in the upper edge of the plate, and these two terminal ends of the channel are connected through suitable pipes 21 and 22 with the refrigerating unit 8. Thus, the partition plate 11 incorporates, and in effect constitutes, the evaporating coil of the heat exchange system.

It has been found desirable, in some instances, to form the partition 12 after the manner of the partition 11 described above, as shown at 12A in Figure 6, so that this partition also may be connected with the unit 8 and may constitute a

functional part of the evaporating section of the heat exchange system. By reason of the form of the channeled plate, this can be done without material sacrifice of effective space within the cabinet; and it materially increases the potentialities of the cabinet for rapid cooling.

The electric motor 9 is arranged so that its shaft occupies a vertical position, and the motor shaft is connected to a shaft 23 which extends downwardly through the top cover member 7, see Fig. 1, and has its lower end journaled in a fixture 24 which is secured at one side and near the bottom of the partition 12. The fixture 24 is hollow and has one open end in registration with an aperture in the partition 12 to which it is secured. The fixture 24 also has an opening 25 at the top through which the shaft 23 passes, and on the shaft and housed within the fixture is a propeller 26, preferably of the screw type as shown. Rotation of the shaft and of the propeller 26 will necessarily set up a fluid flow through the fixture 24 from one of the openings to the other, and from one of the main compartments 14 and 15 to the other, depending upon the direction of propeller rotation.

Attention is directed to the fact that the partition 11 is mounted in a slightly inclined position with respect to the vertical, said partition leaning slightly toward the rear wall 4 of the cabinet. It is to be noted further that the chamber 13 and the partition 11 being located at the rear of the cabinet underlie the top cover members 5-5 so that when the retaining screws 6 are removed, the latter may be folded forwardly on the hinges 27 onto the tops of the associated top cover members 2, thereby affording access to the chamber 13 and to the partition 11. The central portion of the chamber 13 which underlies the top cover member 7 may be easily reached from the opposite sides through the openings afforded by removal of the top cover members 5-5, as described.

The operation of the cabinet is essentially the same as that of the cabinet described in the aforesaid Patent No. 2,188,839. The cabinet is charged with a predetermined amount of water to a level well below the tops of the partitions 11 and 12. The water level in either of the compartments 14 or 15 may be built up at the expense of the level in the other compartment by operation of the motor 9 and of the propeller 26. The water builds up in the one compartment to the point where it overflows the partition 11 into the chamber 13, the water then passing downwardly in the chamber 13 under partition 12 in this compartment, upwardly at the other side, and again over the partition 11 into one or the other of the compartments 14 and 15. From here, it is again drawn by the propeller 26 into the adjoining main compartment for recirculation over the partition 11.

This circulation and re-circulation of the water over the refrigerating partition plate 11 effects a rapid cooling of the water, the operation in this respect being highly efficient by reason of the extended service of the refrigerating plate 11 which is available for direct contact with the circulating water. By reason of the slight inclination of the plate 11, as previously described, the water in passing over the top of the plate from the chamber 13 to one or the other of the compartments 14 and 15 is caused to flow down and over the surface of the plate so as to have a maximum contact with the latter. The arrangement makes possible the use of refrigerating tem-

peratures calculated to build up on the plate 11 an ice bank 28, see Figs. 2 and 3, this bank acting to maintain a suitably low temperature in the water in the cabinet and aiding in the rapid reduction or transfer of temperature from the milk when the containers of relatively warm milk are first placed within the cabinet for the cooling operation.

While I have shown the partition 12 centrally located, it will be understood that this partition may be off-center without departure from the invention, and in some instances such off-center arrangement is desirable. Thus, in the larger sizes of cabinet the water-to-milk ratio decreases, and it is sometimes desirable to have one of the main compartments 14 and 15 somewhat larger than the other so that when the smaller compartment is flooded to overflow, sufficient water may still remain in the larger compartment to cover the pump port and to prevent sucking of air by the pump and interruption of the normal circulation.

I claim:

1. In a milk cooler, a cabinet forming a container for a liquid cooling medium, a plate extending between two opposite walls of the cabinet and in proximity to a third wall and dividing the interior of the cabinet into two chambers of which one embraces a major part of said interior; said plate being adapted to constitute an evaporator unit of a refrigerating system, a second partition of greater height than and extending transversely of the first and dividing the last named chamber into two compartments, and means for building up the liquid level in one of the compartments at the expense of the level in the other and to an extent causing overflow of the first partition.

2. In a milk cooler, a cabinet forming a container for a liquid cooling medium, a plate extending between two opposite walls of the cabinet and in proximity to a third wall and dividing the interior of the cabinet into two chambers of which one embraces a major part of said interior, said plate being adapted to constitute an evaporator unit of a refrigerating system, a second partition of greater height than and extending transversely of the first and dividing the last named chamber into two compartments, said transverse partition extending over the first partition and downwardly into the lesser of the said chambers so as to partition the upper part only of the latter, and means for building up the liquid level in one of the compartments at the expense of the level in the other to an extent causing overflow of the first partition.

3. In a milk cooler, a cabinet forming a container for a liquid cooling medium, a plate extending between two opposite walls of the cabinet and in proximity to a third wall and dividing the interior of the cabinet into two chambers of which one embraces a major part of said interior, said plate being inclined toward said third wall and being adapted to constitute an evaporator unit of a refrigerating system, a second partition of greater height than and extending transversely of the first and dividing the last named chamber into two compartments, and means for building up the liquid level in one of the compartments at the expense of the level in the other and to an extent causing overflow of the first partition.

4. In a milk cooler comprising a cabinet forming a container for a liquid cooling medium, said apparatus including an evaporator plate mounted in the cabinet as a partition dividing the interior

into two chambers one of which embraces the major part of said interior, a second partition of greater height than and extending transversely of the first and dividing the last named chamber into two compartments, means for building up the liquid level in one of the compartments at the expense of the level in the other and to an extent causing overflow of the first partition, and a top closure for the cabinet including a displaceable lid over each of said compartments and an intermediate portion affording a support for said refrigerating apparatus.

5. In a milk cooler comprising a cabinet forming a container for a liquid cooling medium and refrigerating apparatus for cooling said medium, said apparatus including an evaporator plate mounted in the cabinet in proximity to the rear wall thereof as a partition dividing the interior into front and rear chambers, the front chamber embracing a major part of said interior, a second partition of greater height than and extending transversely of the first and dividing the last named chamber into two compartments, means for setting up a circulation of the liquid medium between said compartments and over the first partition, a top closure for the cabinet in-

cluding a displaceable lid over each of said main compartments and an intermediate portion forming a support for the refrigerating apparatus, said lids terminating short of the rear wall of the cabinet, relatively fixed members extending from the rear edge of each of the lids to the rear wall of the cabinet, and means providing for the detachment of said members so as to afford access to the rear chamber and to said plate.

10 6. In a milk cooler, a cabinet forming a container for a liquid cooling medium, a plate extending between two opposite walls of the cabinet and in proximity to a third wall and dividing the interior of the cabinet into two chambers of which one embraces a major part of said interior; a second plate of greater height than and extending transversely of the first and dividing the last named chamber into two compartments, said plates being adapted to constitute elements of an evaporator section of a refrigerating system, and means for building up the liquid level in one of the compartments at the expense of the level in the other and to an extent causing overflow of the first partition.
